J. BERG

WEATHERPROOF CONTAINER

Filed Aug. 9, 1923

FIG. 2

FIG. 3

FIG. 1

FIG. 4

FIG. 5

Witnesses:

Alvin

H. D. Penney

Inventor:
Joseph Berg

By his Atty J. F. Richard

UNITED STATES PATENT OFFICE.

JOSEPH BERG, OF BROOKLYN, NEW YORK.

WEATHERPROOF CONTAINER.

Application filed August 9, 1923. Serial No. 656,538.

To all whom it may concern:

Be it known that I, JOSEPH BERG, a citizen of the United States, residing in Brooklyn, in the county of Kings and State of New York, have invented certain new and useful Improvements in Weatherproof Containers, of which the following is a specification.

The present invention relates to trunks or boxes, and particularly to trunks or boxes which may be carried in a suitable position on automobiles, and one object of the invention is to provide a trunk or box of this character which may be directly exposed to the inclemency of the weather and adapted to prevent injury to its contents therefrom.

Another object is to provide a trunk or box of the character described which is of light weight, compact, strong and durable.

20 A feature of the invention resides in the hinged connection of the lid to the body portion of the trunk or box, whereby when the lid is in normal position entrance of rain or snow into the trunk or box is prevented.

25 Another feature of the invention resides in the lid having water tight hinged connection to the body of the trunk or box, the lid being self supported when in open position in the horizontal plane of the upper edge 30 of the body portion without the use of straps or braces, and out of the way and free from liability to fall into closing position.

I attain the above objects and such other objects as may appear during the subjoined 35 description by way of example of one of the possible embodiments of the invention, shown in the accompanying drawing forming part of this specification, in which Figure 1, is a perspective view, the lid being 40 in open position.

Figure 2, is a sectional view on the line 2—2 of Fig. 1, the lid being in closing position.

Figure 3, is a fragmentary rear view of 45 the upper portion of the trunk or box, the lid being in closing position.

Figure 4, is a detail view of a corner cap and supporting bracket appurtenant to the hinged connection of the lid to the body 50 portion, and

Figure 5, is a fragmentary sectional view on the line 5—5 of Fig. 1.

Similar reference characters denote similar parts throughout the several views.

55 The invention comprises in its main parts or elements the body member generally de-

noted by 10 and the lid generally denoted by 11.

The body member 10 is made of any suitable light weight, strong and rigid material, 60 preferably metal, and is of box form, having the front and rear sides 12 and 13, ends 14 and 15, and bottom 16. The body member 10 is reduced in length and width near its top, as at α , to provide a shoulder or ledge 17 which extends along the front and ends of the member, the distance on the body member from the upper side of the shoulder 17 to the top of the member being substantially the depth of the lid 11 at the 70 front and sides thereof. The body portion 10 at the top of its rear side 13 is curved inwardly, as at 18, Figs. 1 and 2, for the length of the rear side, for the purpose later stated. 75

The body member 10 at each of its four lower corners is provided with the protective corner caps 19, suitably secured, as by rivets, to the body member. The body member 10, at the intersections of its front side and ends near its top, is provided with protective corner caps, generally denoted by 20, each of which comprises the angular securing plates 21 and the angular plate extensions 22, there being shoulders 23 formed between the securing plates 21 and plate extensions 22 which provide on the under side of these corner caps depressed portions adapted to engage or rest upon the shoulder 17 of the body member 10, when the corner caps are suitably secured as by rivets to the body member, the plate extensions 22 lying snugly against the front and sides of the body member and providing guiding surfaces for the lid 11 when moved to closing position, the plate extensions 22 in length being the distance on the body member from the shoulder 17 to the top of said member. 95

For cooperating in hingedly connecting the lid 11 to the body member 10, the corner caps and supporting brackets, generally denoted by 24, are provided. 100

Each of the corner caps and supporting brackets 24 comprises the angular securing plates 25 and the supporting bracket 26 105 forming part of one of the securing plates 25 and lying in the same plane therewith.

The securing plates 25 of the corner caps and supporting brackets 24 are secured, as by rivets, to an end and the rear side of the body member 10 on the outer face thereof below the shoulder 17, the upper edges of 110

the securing plates 25 being flush with the top of the shoulder 17 and the ends of the supporting brackets 26 extending slightly above the top of the body member, the supporting brackets 26 thus being arranged in opposed relation on the ends of the body member at the rear and projecting slightly above the top of the body member, and being spaced away from the outer faces of the ends of the body member by the width of the shoulder 17.

Each of the supporting brackets 26 has rigidly secured to its upper end at right angle thereto the stub shaft 27, the purpose 15 of which is later stated.

The lid 11 is of the same material as the body member 10 and comprises the front side 28, ends 29 and 30 and covering portion 31, the lid being open at its rear, the terms 20 front and rear here being used relative to the lid when it is in closing position.

The lid 11 in length, width and height is arranged to overlap or nest snugly over the reduced portion x of the body member 10, 25 the lower edges of the front side and ends of the lid resting on the shoulders 23 of the corner caps 20, when the lid is in closing position, the ends of the lid lying inside of the supporting brackets 26 of the corner 30 caps 24.

The lid 11 is provided on the free edge of the covering portion 31 with the upturned or rolled hollow, substantially cylindrical portion 32 which is adjacent to and received in 35 the inwardly curved portion 18 of the body member 10, and cooperates therewith for providing an anti-weather device, and also cooperates with the stub shafts 27 of the combined corner caps and supporting brackets 40 26 for providing hinged connection between the body member 10 and lid 11.

The lid 11 at the intersection of its front side 28, ends 29 and 30 and covering portion 31, is provided with corner caps such as 33.

45 The bottom 16 of the body member 10 is offset as at 34, Fig. 5, thereby providing a flange and permitting attachment by any suitable means to the bottom 16 of the wear strips 35 of hard wood or other suitable material.

For assembling the body member 10 and lid 11, the stub shafts 27, prior to securing the corner caps and supporting brackets 24 to the body member 10, are inserted through 55 holes, not seen, but readily understood, arranged in the lower rear corners of the ends of the lid, and are received in the ends of the substantially cylindrical portion 32 of the lid; the corner caps and supporting

60 brackets 24 then being secured to the body member 10, as before described, and hinged connection provided between the lid and body member.

When the lid is moved to covering position 65 the cylindrical portion 32 of the lid 32 is

brought into the position relative to the inwardly curved portion 18 of the body member shown in Fig. 2, and entrance of rain or snow between the lid and body member is prevented, the overlapping or nesting feature of the lid also conducing to keep the body member rain and snow proof.

When the lid 11 is in uncovering position the cylindrical portion 32 bears upon the edge or shoulder 36 of the inwardly curved portion 18 of the body member 10, and is thus supported in the horizontal plane of the upper edge of the body member.

Having thus described my invention, it should be understood that there may be modifications thereof and variations therein without departing from the spirit of the invention or exceeding the scope of the appended claims.

What I claim and desire to protect by 85 Letters Patent is:—

1. A box-like structure comprising, a body member, said body member having a cylindrical indent at one side thereof, a lid for the body member, a cylindrical portion on said lid cooperating with the cylindrical indent on said body member to form a means for preventing the entrance of rain or snow therebetween when the lid is in covering position relative to the body member.

2. A box-like structure comprising, a body member; a lid for the body member; and means comprising a substantially cylindrical portion of the lid formed the full length thereof and cooperating with supporting braces on the body member for movement of the lid to and from position for covering the body member.

3. A box-like structure comprising, a body member; a lid for the body member; means comprising a substantially cylindrical portion of the lid formed the full length thereof and located substantially at the top plane of the body member for cooperating with the body member for connecting the lid to the body member for movement of the lid to and from position for covering the body member; and an inwardly curved portion of the body member formed the full length thereof and cooperating with said substantially cylindrical portion for preventing entrance of rain or snow between the lid and body member when the lid is in covering position.

4. A box-like structure comprising, a body member; a three-sided lid for the body member; means comprising a substantially cylindrical portion of the lid formed the full length thereof and cooperating with the body member for connecting the lid to the body member for movement of the lid to and from position for covering the body member; and an inwardly curved portion of the body member located at the top plane of the body member and cooperating with

- 5 said substantially cylindrical portion for preventing entrance of rain or snow between the lid and body member when the lid is in covering position; said inwardly curved portion having a shoulder at its top engageable with said substantially cylindrical portion for supporting the lid in horizontal uncov- 65
5 ering position.
- 10 5. A box-like structure comprising, a body member having a reduced portion on its front side and ends, a three-sided lid for the body member adapted when in covering position to overlap at said reduced portion at said side and ends; a lid for said body 70
15 member having a weatherproof hinge, said body member having brackets for engaging the said cylindrical portion of the lid for hingedly connecting the same to the body member, said hinge being located near the 75
20 top plane of the lid and the body member, the said body member having an indented semi-cylindrical portion whereby to house said hinge and to hold the lid when open in substantially horizontal position.
- 25 6. A box-like structure comprising, a body member having a reduced portion on its front side and ends near the top thereof providing a shoulder on said front side and ends; a lid for the body member adapted 80
30 when in closing position to overlap said reduced portion, and provided with a sub- 85
35 stantially cylindrical portion hollow at its ends; corner caps secured to the front side and ends of the body member conformably engaging said front side and ends and providing shoulders on said front side and ends engaging over the first mentioned shoulder; the lid when in covering position overlapping the reduced portion of the body member; said inwardly curved portion being provided with a shoulder engageable with said substantially cylindrical portion for supporting the lid in horizontal uncov- 90
